(57) **CLAIM**

The ornamental design for a pitcher body, as shown and described.

DESCRIPTION

FIG. 1 is a front top perspective view of the new design.

FIG. 2 is a rear top perspective view of the new design.

FIG. 3 is a right side view of the new design.

FIG. 4 is a left side view of the new design.

FIG. 5 is a front view of the new design.

FIG. 6 is a rear view of the new design.

FIG. 7 is a top view of the new design showing the inside of the pitcher body, which forms no part of the claimed design.

FIG. 8 is a bottom view of the new design; and,

FIG. 9 is a front top perspective view of the new design, together with an unclaimed associated lid for the pitcher body illustrated in dash-dot lines.

The dash lines shown in the drawings illustrate portions of the pitcher body that form no part of the claimed design. The dash-dot lines shown in FIG. 9 illustrate environmental structure of an associated lid that forms no part of the claimed design. The shading lines shown in the drawings represent the approximate three-dimensional contour of the claimed design and are not intended to indicate surface decoration.
